Primary Examiner — Darcey E Gottschalk*Assistant Examiner* — Isabelle S Farineau(74) *Attorney, Agent, or Firm* — Muncy, Geissler, Olds & Lowe, P.C.(57) **CLAIM**

The ornamental design for a ceiling light as shown and described.

DESCRIPTION

FIG. 1 is a perspective view of a ceiling light embodying my new design;

FIG. 2 is another perspective view of the claimed design;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof; and,

FIG. 8 is a bottom plan view thereof.

The broken lines depict portions of the ceiling light that form no part of the claimed design.
